RAILWAY SIGNALING SYSTEM

John W. Logan, Jr., Forest Hills, Pa., assignor
to The Union Switch & Signal Company,
Swissvale, Pa., a corporation of Pennsylvania

Application January 14, 1939, Serial No. 250,960

18 Claims. (Cl. 246—161)

My invention relates to railway signaling systems, and is particularly well adapted for, but not limited thereto, railway signaling systems of the type adapted to govern the operation of a control lever of an interlocking machine, which lever is normally controlled over interlocking circuits but which is controlled at times by a time release device independently of such interlocking circuits.

10 An object of my invention is the provision, in a railway signaling system of the class described, of novel and improved means whereby the operation of a time release device is prevented at all times except when it is necessary to govern the 15 control lever by such time release device.

Another object of my invention is the provision in a time release device capable of storing energy the expenditure of which is governed to provide a predetermined time interval, of novel and improved means for at times preventing the expenditure of the energy stored in such device.

Other objects and advantages of my invention will appear as the specification progresses.

I shall describe one form of apparatus embodying my invention, and shall then point out the novel features thereof in claims.

In the accompanying drawing, Fig. 1 is a vertical sectional view showing one form of a time release device provided with means embodying my invention for at times preventing operation of such device. Fig. 2 is a vertical sectional view taken on the line 2—2 of Fig. 1. Fig. 3 is a vertical sectional view taken on the line 3—3 of Fig. 2. Fig. 4 is a diagrammatic view of a typical control circuit which may be used for controlling a time release device embodying my invention when applied to a railway interlocking plant.

Referring to the drawing, the reference character J designates as a whole a time release device which may take any one of several suitable forms, and as here shown is of the type illustrated and described in United States Letters Patent No. 1,802,367, granted on April 28, 1931, to A. P. Bartusch and G. V. Jefferson, for Time 40 release mechanism. Device J will be described in connection with the present description only insofar as is necessary for a complete understanding of my invention, and as shown comprises in its essential elements, motor means 45 capable of storing energy, and control means operatively connected by means of a gear train with such motor means for controlling the rate at which energy stored within such motor means is expended. The motor means of device J comprises a member 5 rotatable in two directions,

and biased to return in one direction to a normal position by means of a spring 6 (see Fig. 3) having one end fastened to a normally non-rotatable shaft 4 and the other end connected with member 5. Member 5 is provided with a gear segment 7 adapted to be engaged by a pinion gear 8 forming a part of the gear train which operatively connects the control means of device J with the motor means. This train of gears comprises, in addition to pinion 8 mounted on a shaft 9 for intermeshing with gear segment 7, a gear wheel 10 rotatably mounted on shaft 9 and provided with a pair of pawls 11 which are biased by a spring 12 into engagement with the teeth of a ratchet wheel 13 fixed on shaft 9 in juxtaposition with gear 10, the pawls 11 and wheel 13 cooperating to permit wheel 13 to be rotated in a clockwise direction (as viewed in Fig. 1) without effecting rotation of gear 10, but effecting rotation of gear 10 in the event that wheel 13 operates in a counterclockwise direction. Gear wheel 10 is mounted in intermeshed engagement with a pinion 14 rotatably mounted on a shaft 15, and which shaft 15 forms a part of the control means for device J.

The control means which controls the rate at which energy stored in the motor means of device J is expended, comprises an escapement wheel 16 fixed on the shaft 15, the teeth of which wheel 16 are engaged by the pallets of an escapement 30 bar 17 fixed to a rockshaft 18. Rockshaft 18 has mounted thereon a pendulum 19, which controls the oscillations of the shaft to thereby control the rate at which the energy stored within the motor means of device J is expended.

The device J is further provided with means for rotating member 5 against its spring bias for storing energy in the motor means of the device. As shown, the means comprises a vertically disposed contact operating member or rod 20, which is operatively connected with member 5 by means of a crank member 21, and which operates through a guide portion provided in an upper supporting member 22 to engage a segment 23. The segment 23 may be the lever segment provided for a control lever of an interlocking machine, and as shown is provided on each end with a cam 24. The time release device is adapted to be secured in fixed relation with a supporting member or frame 25 by means of a supporting lug 26, but segment 23 is adapted to swing to the right or left in response to a movement of the control lever to a right or a left control position. Rod 20 is normally biased into engagement with segment 23 by virtue of the 55

action of spring 6 upon rotatable member 5, and is adapted to be depressed to rotate member 5 in a counterclockwise direction (as viewed in Fig. 1) against its spring bias thereby actuating 5 spring 6 to store energy in such spring, when segment 23 is swung to either control position wherein cam 24 actuates rod 20. The rotation of member 5 in a counterclockwise direction in response to the actuation of rod 20 actuates 10 pinion 8 and ratchet wheel 13 of the gear train in a clockwise direction, but as was pointed out hereinbefore, the actuation of ratchet wheel 13 is not transmitted to gear wheel 18 since the inclination of the teeth of wheel 13 permits the 15 teeth to pass underneath pawls 11 without transmitting rotary motion to gear wheel 18.

In order to permit the lever and segment to be swung from its intermediate or normal position as shown to and from its control positions 20 without effecting unnecessary operation or expenditure of energy of the time release device J, I provide latching means for controlling the operation of the device. The latching means for device J comprises in its essential elements a 25 locking member 30, biased into engagement with either the control means of the device or the gear train connecting such control means with the motor means of the device J, and which member 30 is adapted to be controlled by an electromagnet 30 30 27 against its bias out of latching engagement with the device J to permit the operation of the device. As herein shown, the latching means comprises electromagnet 27 suitably fastened to supporting member 22, and provided with an 35 armature 28 pivotally attached to upper supporting member 22. Armature 28 is operatively connected by means of a horizontally extending member 29 with locking member 30, the locking member 30 being biased by means of a 40 spring 31 connected with member 29 and with a supporting lug 32 fastened on the supporting member 22, into engagement with escapement bar 17. The biased engagement of locking member 30 with escapement bar 17 forces 45 one pallet of the bar into engagement with escapement wheel 16, and thereby prevents the escapement means from operating by over-balancing the effective force of pendulum 19 attached to rock shaft 18. The armature 28 is so 50 connected with locking member 30 that in the event electromagnet 27 is energized to attract armature 28, locking member 30 is actuated out of engagement with escapement bar 17, thereby permitting the escapement means to operate and 55 pendulum 19 to govern the oscillation of rock shaft 18 to control the rate of return of the member 5 to its normal position in response to its bias. It is to be understood, of course, that while locking member 30 is herein shown biased into 60 engagement with escapement bar 17, the member 30 may be biased into engagement with escapement wheel 16, or with any suitable portion of the gear train connecting the escapement mechanism with the motor means of device J, the essential feature of the latching means being the 65 biased engagement of member 30 with the device J prevents operation of the device in response to the energy stored in the motor means of the device.

70 With the apparatus constructed in the manner just described, it is apparent that once segment 23 is swung to one of its control positions so that rod 20 is depressed and member 5 is rotated against its bias, member 5 is retained in its 75 rotated position to retain the energy stored in the

motor means until such time as the segment is swung away from its control position wherein cam 24 engages rod 20, and magnet 27 is energized to attract armature 28. That is to say, once member 5 is rotated against its spring bias, 5 the return of the member to its normal position when the segment is swung to its mid position is prevented by the deenergized condition of magnet 27 preventing the operation of the control means for device J. It follows, therefore, that once member 5 is actuated to its rotated position to store energy within the motor means of device J, and as long as magnet 27 is deenergized, the lever may be freely swung into its control and mid positions without effecting operation of the 10 time release device.

With device J in the condition just described, that is, with the lever moved out of its control position so that segment 23 no longer actuates rod 20 (the rod being retained in its depressed position by virtue of the latching means provided for the device), operation of the device may be effected by energizing magnet 27. When this happens, the movement of armature 28 to its attracted position is transmitted through member 29 to locking member 30, thus actuating member 30 out of engagement with escapement bar 17 and permitting pendulum 19 to control the oscillation of rock shaft 18, and thereby permitting the escapement means to control and retard the return of member 5 to its normal position in response to the expenditure of energy stored within the motor means of device J.

Referring now to Fig. 4, a railway signaling system is shown wherein the operation of a time release device, which is effective when operated to govern the operation of a control lever, is controlled to prevent operation of such device except when such operation is necessary to effect control of the lever. In Fig. 4, the reference character 35 designates a control lever which may be adapted to control railway traffic controlling apparatus, such as signal S, by virtue of control circuits omitted from the drawing for the sake of clearness since they form no part of my present invention. As indicated in Fig. 4, lever 35 is preferably a control lever provided for a railway interlocking system.

Railway interlocking systems are usually so arranged that when a control lever is operated to 50 condition its traffic controlling apparatus for a train movement, further operation of the control lever in a manner to interfere with the established train movement is prevented by means of a lever lock magnet. The lever lock magnet for 55 each control lever is usually governed by well-known interlocking circuits, arranged to energize the lever lock magnet for a control lever after the function of the control apparatus governed by such lever is completed, so that the lever may be 60 operated to a new position. Under normal conditions, the interlocking circuits are conditioned by the movement of the train past the control apparatus, to release the control lever for such control apparatus. At times, however, it is necessary or desirable to operate a control lever which has been operated to condition its control apparatus for a train movement, to a new position 65 prior to the train passing such apparatus. This latter is an abnormal condition, and it has been 70 found desirable to enforce a predetermined time interval between an initiation of the operation of a control lever under this abnormal condition, and the movement of the lever to the new position. The predetermined time interval is usually 75

provided by means of a time release device, such as device J previously described. Device J is adapted to close a circuit controlling contact 38-39 (see Fig. 2) when rod 20 is in its normal 5 or contact closing position, the contact 38-39 being opened when rod 20 is in its depressed or contact opening position.

The control lever 35 shown in Fig. 4 is adapted to be moved to a plurality of positions, one of 10 which is a mid or normal position, and at least one of the other positions being a control position. As indicated in the diagram immediately below lever 35 in Fig. 4, the lever is adapted to be moved to an extreme left control position L, a 15 left indication position B, a mid or normal position N, a right indication position D and an extreme right control position R. The lever is provided with control contacts, two of which are indicated on the drawing by the reference characters 20 LB and RD, contact LB being closed when the lever is in or intermediate its left L or left indication B positions, and contact RD being closed when the lever is in or intermediate its right R or right indication D position. The lever 25 35 is provided with locking means for controlling the operation of the lever, comprising a segment 36 secured to the lever and engageable by a locking dog 37 disposed in magnetic relationship with a lock magnet 34, the arrangement being such 30 that when lever 35 is moved to either extreme control position, locking dog 37 engages segment 36 to prevent the lever from being moved toward its mid position past the indication position intermediate such control position and the mid 35 position, unless magnet 34 is energized to actuate locking dog 37 out of engagement with segment 36. Lever 35 is also provided with a segment 23 (see Fig. 1) provided on each outer end with a 40 cam 24, and with a time release device J, the rod 20 (see Fig. 2) of device J being biased into engagement with the segment 23 of lever 35. It is readily apparent that if rod 20 of device J is in its normal or contact closing position, the operation of lever 35 to either one of its extreme 45 positions actuates rod 20 into its depressed or contact opening position, thereby storing energy within the motor means of device J, and if lever 35 is then restored to its mid position, rod 20 is retained at its contact opening position and the 50 energy within device J is retained stored, unless magnet 27 of the latching means for device J is energized.

In accordance with an object of my invention, I provide remotely controlled means for preventing 55 the operation of time release device J except when such operation is necessary to effect control of lever 35. That is to say, the means controlling device J is arranged so that under ordinary conditions, once lever 35 is operated so that rod 20 60 of device J is depressed to its contact opening position and energy is stored within the device, subsequent operations of lever 35 under normal conditions do not effect the expenditure of the 65 energy stored within device J and consequent return of rod 20 to its contact closing position. As shown in Fig. 4, magnet 27 of the latching means 70 for device J is provided with an energizing circuit passing from one terminal A of a suitable source of current, such as a battery not shown, through back contact 40 of a track relay TR1, front contact 41 of a track relay TR2, lever contact LB or RD of lever 35, and the winding of magnet 27 of device J to the other terminal C of the source of current. Relay TR1 as shown is 75 usually the track relay provided for the track

section in approach of signal S controlled by lever 35, and relay TR2 is usually the track relay provided for the track section in advance of signal S. It is readily apparent that magnet 27 of device J is energized to permit device J to operate its 5 contact 38-39 closed only in the event that a train is on the approach section for signal S. It can be seen that, with magnet 27 of device J energized, an initial movement of lever 35 to move rod 20 of device J out of engagement with 10 segment 23 of lever 35 results in the operation of device J in response to the energy stored therein. As was pointed out heretobefore, operation of lever 35 to a new position while a train is on the section in approach of signal S governed by lever 15 35, is an abnormal condition requiring an enforcement of the predetermined time delay. It follows that with rod 20 of device J operated to its contact opening position, any movement of the lever 35 under normal conditions will result 20 in maintaining the energy stored in device J since magnet 27 is not energized under normal conditions, but that under abnormal conditions when magnet 27 is energized and lever 35 is moved to operate segment 23 out of engagement 25 with rod 20, the device J operates its rod 20 to the contact-closing position, the actuation of the rod being controlled at a uniform rate as was pointed out hereinbefore to provide a predetermined time interval prior to contact 38-39 closing. When contact 38-39 closes, a simple circuit 30 passing from terminal A through contact 38-39 of device J and the winding of lock magnet 34 of lever 35 to terminal C is completed, whereupon lever 35 is unlocked and can be operated to its 35 new position independently of the interlocking circuits.

From the foregoing, it is readily apparent that I have provided traffic controlled means effective 40 to maintain energy stored within a time release device during all operations of the control lever under normal conditions, but releasing the energy stored to permit the time release device to control the operation of the control lever under abnormal conditions. It is readily apparent that 45 since unnecessary operation of the time release device is prevented, undue wear of the operating elements of the device is prevented. It is further apparent that since the control lever actuates the contact operating member to its contact 50 opening position only after the member has been released to its contact closing position due to the abnormal conditions hereinbefore referred to, the operating load on a control lever is considerably lessened during normal operations of the 55 lever.

Although I have herein shown and described only one form of apparatus embodying my invention, it is understood that various changes and modifications may be made therein within 60 the scope of the appended claims without departing from the spirit and scope of my invention.

Having thus described my invention, what I claim is:

1. In combination with a time release device 65 controlled by the operation of escapement means having an escapement bar engaging an escapement wheel, latching means for biasing said escapement bar into engagement with said escapement wheel for preventing the operation of 70 said escapement means, and magnetic means for controlling said latching means for permitting said escapement means to operate.

2. In combination with a time release device controlled by the operation of escapement means 75

having an escapement bar engaging an escapement wheel, spring biasing means for biasing said escapement bar into engagement with said escapement wheel for preventing the operation of said escapement means, and magnetic means for controlling said spring biasing means for permitting said escapement means to operate.

3. In combination with a time release device controlled by the operation of escapement means 10 having an escapement bar engaging an escapement wheel, a locking member, means for biasing said locking member into engagement with said escapement bar for preventing the operation of said escapement means, an electromagnet, and means governed by said electromagnet 15 for moving said locking member against its bias out of engagement with said escapement bar.

4. The combination with a time release device controlled by the operation of escapement means 20 having an escapement bar engaging an escapement wheel, of magnetic latching means for said escapement means comprising an electromagnet having an armature, a locking member operatively connected with said armature for movement to a disengaged position when said electromagnet is energized, and means effective when said electromagnet is deenergized for biasing said locking member into an engaged position with said escapement bar for preventing the operation 25 of said escapement means.

5. A time release device comprising a member movable in two directions, a spring normally biasing said member in one direction to a normal position, means for moving said member in 30 the other direction against the bias of said spring to another position, an escapement mechanism for retarding the return of said member from said other position to its normal position, and latching means operatively connected with 35 said member for at times preventing said member from returning to its normal position in response to its bias.

6. A time release device comprising a member movable in two directions, a spring normally biasing said member in one direction to a normal position, means for moving said member in 40 the other direction against the action of said spring to another position, an escapement mechanism operatively connected with said member and effective when operating for retarding the return 45 of said member to its normal position, and latching means for said escapement mechanism effective at times for preventing the operation of such mechanism whereby said member is prevented from returning to its normal position.

55. 7. In a time release device of the type wherein a member movable in two directions is biased to return in one direction to a normal position and is provided with escapement means for controlling the return of said member in response to its bias to said normal position, the combination with said escapement means of a magnetic latch effective at times to prevent the return of said member in response to its spring bias to said normal position.

8. In a time release device of the type wherein a member movable in two directions is biased to return in one direction to a normal position and provided with escapement means for controlling the return of said member in response to its bias to said normal position, the combination with said escapement means of a locking member normally biased into engagement with said escapement means for conditioning said escapement means to prevent the return of said 75

first member to its normal position, and electromagnetic means operatively connected with said locking member for at times withdrawing said member from engagement with said escapement means whereby said escapement means is conditioned to control the return of said first member to its normal position.

9. In combination with a lever of an interlocking machine, a time release device having a motor means, means operable when said lever is moved to a control position for storing energy in said motor means, and remotely controlled means for at times retaining the energy stored in said motor means when said lever is moved away from its control position.

10. In combination with a manually operable lever adapted to control railway signaling apparatus, said lever operable to a normal and to a control position, locking means for controlling the operation of said lever, a time release device 20 having a contact operating member biased to a first position and operable to a second position, means governed by said contact operating member for controlling said locking means, means effective when said lever is operated to its control position for operating said contact operating member to its second position in opposition to its bias, and remotely controlled means effective at times for maintaining said contact operating member in its second position when said 25 lever is operated to its normal position.

11. In combination with a lever adapted to control railway signaling apparatus governing traffic on a stretch of railway track, said lever operable to a normal and to a control position, locking means for controlling the operation of said lever, a time release device having a contact operating member biased to a first position and operable to a second position in opposition to its bias, means effective when said contact 40 operating member is in its first position for controlling said locking means, means effective when said lever is operated to its control position for operating said contact operating member to its second position, and traffic controlled means for 45 maintaining said contact operating member in its second position when said lever is restored to its normal position.

12. In a railway interlocking system of the type wherein the operation of a control lever is governed by locking means controlled under normal conditions by interlocking circuits and under abnormal conditions the locking means is controlled by a time release device adapted to provide a predetermined time interval prior to 55 a contact operating member of such device being operated to its contact closing position wherein said locking means is controlled, the combination with such time release device, of means operative when said contact operating 60 member is operated to its contact opening position in response to the operation of said control lever to its control position for maintaining said contact operating member at its contact opening position during all subsequent movements of 65 said control lever until such time as said abnormal conditions require the operation of said contact operating member to its contact closing position.

13. In a railway interlocking system of the type wherein the operation of a control lever is governed by locking means controlled under normal conditions by interlocking circuits and under abnormal conditions the locking means is controlled by a time release device adapted to 70 75

provide a predetermined time interval effected by the expenditure of energy stored within such device prior to such device establishing control over said locking means, the combination with 5 such locking means of a time release device comprising motor means adapted when said control lever is operated to a control position for storing energy in said time element device, means for maintaining the energy stored in such device 10 during all subsequent lever operations under normal conditions, and means effective during abnormal conditions for releasing the energy stored within such time release device for establishing control by such device over said locking 15 means.

14. In combination, a stretch of railway track provided with a track section including a track relay, a signal for controlling traffic operating over said track section, a lever for controlling 20 said signal, contacts for said lever, a lever lock for controlling the operation of said lever, a time release device for controlling said lever lock, and means governed by said track relay and said lever contacts for at times preventing the operation 25 of said time release device.

15. In combination, a stretch of railway track provided with a track section including a track relay, a signal for controlling traffic operating over said track in advance of said track section, 30 a lever for controlling said signal, contacts on said lever, a lever lock for controlling the operation of said lever, a time release mechanism for controlling said lever lock, means for preventing said time release device from controlling 35 said lever lock, and circuit means governed by said track relay and said lever contacts for rendering said means ineffective to prevent said time release device from controlling said lever lock.

16. In a time release device, a motor, a vertically reciprocable rod operable between two extreme positions, means operatively connecting said rod with said motor and effective when said rod is operated to one of its extreme positions for storing energy in said motor, control means operatively connected with said motor for controlling 40 the rate at which energy stored in said motor is expended to restore said rod to the other 45 position.

of its two positions, latching means operatively connected with said control means for at times retaining said rod in its said one position and for retaining energy stored in said motor, and electromagnetic means for controlling said latching 5 means.

17. In combination with a lever of an interlocking machine, said lever being operable from a normal to a control position, a time release device having a reciprocable rod operable between two extreme positions, means operable when said lever is moved to its control position for operating said rod to one of its extreme positions, motor means operatively connected with said rod and effective at times to operate said 15 rod to the other of its two positions, and remotely controlled means for governing said motor means to be effective to operate said rod at times when said lever is moved from its control 20 position.

18. The combination with a railway interlocking system having a control lever adapted to control railway traffic controlling apparatus provided for a stretch of railway track, said lever being operable to normal and control positions, 25 said lever also having locking means controlled under normal conditions by interlocking circuits to be effective to permit an operation of said lever, of a time release device effective at times to control said locking means to permit operation 30 of said lever, said device having a reciprocable rod operable between two extreme positions, said rod in one of its extreme positions conditioning said device to be effective to control said locking means, said device having means effective when 35 said lever is operated to a control position for operating said rod to the other of its two positions, said device also having motor means effective to operate said rod to its said one position, and means responsive to a movement of said 40 lever and effective when and only when said lever is moved during the interval said interlocking circuits are ineffective to control said locking means for causing said motor means to be effective to operate said rod to its said one 45 position.

JOHN W. LOGAN, JR.
